(57) **CLAIM**

I claim the ornamental design for an antenna for water meter, as shown and described.

DESCRIPTION

FIG. 1 is a perspective view of an antenna for water meter according to an embodiment of the invention.

FIG. 2 is a close-up perspective view taken along the lines 2-2 of the antenna for water meter depicted in FIG. 1.

FIG. 3 is a top plan view of the antenna for water meter depicted in FIG. 1.

FIG. 4 is a front elevation view of the antenna for water meter depicted in FIG. 1; and,

FIG. 5 is a rear elevation view of the antenna for water meter depicted in FIG. 1.

The broken lines illustrate portions of the antenna for water meter which form no part of the claimed invention.

1 Claim, 3 Drawing Sheets
